(57) **CLAIM**

The ornamental design for an application server for short range radio communication, as shown and described.

DESCRIPTION

FIG. 1 is a top, left side perspective view of an application server for short range radio communication showing my new design;

FIG. 2 is a bottom, right side perspective view thereof; FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.
